LOAD TRANSFER DEVICE

Ray Cyrus Yeoman, Lufkin, Tex., assignor to
 Texas Foundries, Inc., Lufkin, Tex., a corpora-
 tion of Texas

Application March 16, 1945, Serial No. 583,031

9. Claims. (Cl. 94—8).

1

This invention relates to load transfer devices and more particularly to devices for transferring loads between adjacent slabs of concrete or the like.

In laying highways, runways, ramps, floors, etc., it is customary to divide the concrete into individual slabs. The spaces or joints between the slabs are filled with an expansible and compressible filler material and the slabs are connected by dowels or like load transfer devices which extend across the joints to transfer the load from one slab to the other.

It is one of the objects of the present invention to provide a load transfer device which is extremely simple and inexpensive to construct and install and which effectively transfers loads from one slab to the other.

Another object is to provide a load transfer device which will permit a limited longitudinal movement of the slab ends at the joint without interfering with the transfer of the loads.

Still another object is to provide a load transfer device which will limit the separation of the slabs at the joint to prevent excessive opening up of the joint and loss of sealing contact between the filler and the slab faces.

A still further object is to provide a load transfer device formed by identical members made up of rods or strips.

The above and other objects and advantages of the invention will be more readily apparent from the following description when read in connection with the accompanying drawing, in which—

Figure 1 is a horizontal section looking from the bottom through a pair of slabs connected by the load transfer device of the invention;

Figure 2 is a vertical section on the line 2—2 of Figure 1;

Figure 3 is a perspective view of the load transfer device;

Figure 4 is a vertical section through an alternative construction;

Figure 5 is a section on the line 5—5 of Figure 4; and

Figure 6 is a perspective view of the alternative device.

As shown in Figures 1 and 2, a pair of adjacent slabs 10 and 11 of concrete or like material are connected at a joint by an expansible filler 12 which engages the adjacent faces of the slabs to seal the joint therebetween. The filler 12 may be any desired type of material such as asphalt, compressed wood or metallic expansible filler strips.

2

To connect the slabs for transfer of loads therebetween a pair of load transfer members which are substantially identical are mounted in the slabs respectively and interengage each other in the space between the slabs. The members, as shown, are formed of rods or wire bent into a U-shape to provide legs 13, extending into the slabs, and preferably turned over at their ends as shown at 14 to anchor the members securely in the slabs. The ends of the members project beyond the slab faces into the joint space between the slabs and are squeezed together to form narrow tip portions 15 extending at right angles from the plane of the members. The sides of each member are spaced apart beyond the slab faces to leave openings through which the tip portion of the other member extends. When the load transfer device is installed in the slabs, the members will connect together as illustrated in Figures 1, 2 and 3 with each of the tip portions 15 extending through the opening provided by the opposite member. The filler strip 12 is preferably formed with openings through which the load transfer devices may extend.

In installing the load transfer devices in slabs, a series of devices are mounted at spaced points along the joint between the slabs. Each of the devices is reversed with respect to the adjacent devices. As seen in Figure 2, a vertical downward force on the slab 11 will be transferred through the load transfer device to the slab 10 due to the bearing of the member carried by the slab 11 on the cooperating member carried by the slab 10. In a similar manner downward forces on the slab 10 will be transferred to the slab 11 through the adjacent load transfer devices whose position is reversed relative to that illustrated. The devices may be of such size and so spaced as to accommodate the maximum expected vertical loads on the slabs.

As the temperature changes, the slabs tend to expand or contract and either to separate or move closer together at the joints. The tip portions 15 of the load transfer members are so interlocked that they will limit the permissible separation of the slabs at the joint so that the slab faces cannot separate far enough to move out of sealing contact with the filler 12. In forming the joints, the filler is preferably made so that it will accommodate the maximum expected separation of the slab faces and the load transfer members may be so installed that they will permit the necessary degree of separation but will engage each other to prevent excessive

separation which might allow the joint to open up.

The tip portions 15 of the load transfer members are preferably coated with plastic material such as rubber, asphalt composition or the like as indicated at 15a. This material serves to locate the members properly relative to each other and to protect them against rust or corrosion. As the slabs expand or contract the plastic material will be compressed between the two tip portions or between the tip portions and the slab faces to accommodate limited movement of the slab faces away from or toward each other as required. Preferably the coating is omitted from the surfaces which transmit vertical loads so that the relative vertical positions of the slabs are fixed.

Figures 4, 5 and 6 illustrate an alternative construction for connecting a pair of slabs 16 and 17 having a filler strip 18 between their adjacent faces. The load transfer device illustrated in these figures is formed of a rod or wire bent back on itself at its center to provide a relatively narrow tip portion 19. Just back of the tip portion the sides of the rod or wire are separated and bent laterally out of the plane of the member as indicated at 21 to provide an opening through the member which is offset from the tip portion 19. Back of the separated portions 21 the sides of the rod are bent together again as indicated at 22 and terminate in projecting tips 23 to anchor the member in the slab.

In installing these devices in the slabs, the tip portion 19 of one member extends through the opening in the other member and into the opposite slab. The tip portions are greased or otherwise coated to prevent adhesion of the concrete thereto. The ends of the tip portions 19 are preferably coated with a plastic material such as rubber or asphalt composition as shown at 24 to yield when the tip portions tend to move into the slabs during expansion thereof. Also the offset sides 21 are similarly coated as indicated at 25 yieldingly to resist horizontal movement of the slabs in either direction and to assist in locating the members during installation. In addition, the coating 25 covers substantially the entire portion of the members which is exposed between the slabs to prevent rust or corrosion thereof.

When installed, the members will occupy the position indicated in Figures 4 and 5 so that vertical loads on the slabs will be transferred through the members from one slab to the other. When the slabs tend to separate due to contraction thereof, the tip portions 19 will slide through the openings to a limited extent but will eventually engage the separated portions 21 to prevent further movement of the slabs. This construction, therefore, operates in substantially the same manner as that of Figures 1 to 3 to transfer both vertical and horizontal forces between the slabs.

While two embodiments of the invention have been shown and described in detail, it will be understood that these are illustrative only and are not intended as a definition of the scope of the invention, reference being had for this purpose to the appended claims.

What is claimed is:

1. A load transfer device for use with adjacent slabs of concrete or the like comprising a pair of identical elongated members arranged in reversed relation and adapted to be imbedded in the slabs respectively throughout the major portion of their length with their end portions projecting beyond the slabs, the end portion of each

member being formed with an opening therethrough and with a reduced tip offset from the opening and of smaller horizontal section and extending through the opening in the other member.

5 10 15 20 25 30 35 40 45 50 55 60 65 70 75 80 85 90 95

2. A load transfer device for use with adjacent slabs of concrete or the like comprising a pair of identical members arranged in reversed relation and adapted to be imbedded in the slabs respectively with their end portions projecting beyond the slabs, the end portion of each member being formed with an opening therethrough and with a reduced tip of smaller horizontal section than the opening extending substantially at a right angle to the member and extending through the opening in the other member.

3. A load transfer device for use with adjacent slabs of concrete or the like comprising a pair of identical elongated members arranged in reversed relation and adapted to be embedded in the slabs respectively throughout the major portion of their length with their end portions projecting beyond the slabs, the end portion of each member being formed with an opening therethrough and with a reduced tip lying substantially parallel to the member, the tip and the portion in which the opening is formed being offset and the tip on each member extending through the opening in the other member.

4. A load transfer device for use with adjacent slabs of concrete or the like comprising a pair of members adapted to be imbedded in the slabs respectively, each member being formed of an elongated strip bent back on itself and adapted to have its end portions imbedded in one of the slabs and its central portion projecting from the slab, the central portion of each strip being spread apart to form an opening through the member and lying close together at the extreme outer end of the member to form a reduced tip, the tip on each member being smaller than the opening and extending through the opening in the other member.

5. A load transfer device for use with adjacent slabs of concrete or the like comprising a pair of members adapted to be imbedded in the slabs respectively, each member being formed of an elongated strip bent back on itself and adapted to have its end portions imbedded in one of the slabs and its central portion projecting from the slab, the central portions of the strip being spread apart to form an opening through the member and lying close together at the extreme outer end of the member to form a reduced tip, the reduced tip on each member lying substantially at a right angle thereto and extending through the opening in the other member.

6. A load transfer device for use with adjacent slabs of concrete or the like comprising a pair of members adapted to be imbedded in the slabs respectively, each member being formed of an elongated strip bent back on itself and adapted to have its end portions imbedded in one of the slabs and its central portion projecting from the slab, the central portions of the strip being spread apart to form an opening through the member and lying close together at the extreme outer end of the member to form a reduced tip, the reduced tip on each member lying substantially parallel thereto and being offset from the spread portions of the strip and extending through the opening in the other member.

7. A load transfer device for use with adjacent slabs of concrete or the like comprising a pair of elongated members adapted to be imbedded

in the slabs respectively with their ends projecting beyond the slabs, the projecting end portion of each of the members being formed with an opening therethrough and with a reduced tip of smaller section than the opening and extending through the opening in the other member, and a coating of plastic material on said reduced tips yieldingly to resist horizontal movement of the slabs.

8. A load transfer device for use with adjacent slabs of concrete or the like comprising a pair of elongated members adapted to be imbedded in the slabs respectively with their ends projecting beyond the slabs, the projecting end portion of each of the members being formed with an opening therethrough and with a reduced tip of smaller section than the opening extending substantially at a right angle to the member through the opening in the other member, and a coating of plastic material over the reduced tips.

9. A load transfer device for use with adjacent slabs of concrete or the like comprising a pair of elongated members adapted to be imbedded in the slabs respectively with their ends projecting beyond the slabs, the projecting end portion
